UNITED STATES PATENT OFFICE

HAROLD KNUTSON, OF CHICAGO, ILLINOIS, ASSIGNOR TO PAUL DICKINSON, INCORPORATED, A CORPORATION OF ILLINOIS

VENTILATOR

Application filed November 19, 1927. Serial No. 234,351.

This invention relates to chimney tops or ventilators and is intended to provide certain novel improvements in a ventilator structure of the type disclosed by Patent 5 No. 1,028,958 issued to Jesse L. Phillips, June 11, 1912, and to improve devices of this character in sundry details hereinafter described and more particularly pointed out in the appended claims.

10 Among other objects, the present invention is intended to provide a simple, durable and efficient structure wherein the strong upward draft through the ventilator is accelerated and a positive discharge from 15 the top thereof is made more certain by reason of increased velocity of the wind at the top of the chimney or ventilator shaft, due to a novel construction and formation of elements comprising the top or hood.

20 One embodiment of the invention is shown for illustrative purposes in the accompanying drawings, in which

Fig. 1 is an elevational view, partly in section, of a chimney or ventilator top embodying my invention, and having portions thereof broken away to illustrate more clearly certain novel features of the invention, and

Fig. 2 is a plan section taken, as indicated by the line 2—2 of Fig. 1.

In the drawings, the numeral 5 designates a section of pipe adapted to be secured to the upper end of a chimney or ventilator flue, and having formed in its 35 upper edge portion a plurality of uniformly spaced notches 6, preferably of substantially V-shaped form.

Secured to the outer surface of the pipe 5 and suitably spaced therearound, preferably adjacent the notches 6, are a plurality of upwardly tapered U-shaped draft members 7 adapted to co-operate with the outer surface of the pipe 5 in a manner to form a plurality of uniformly spaced upwardly 45 tapered passages outside the pipe and adjacent the notches 6.

The upper end portions of the members 7 are adapted to terminate in a plane above the upper edge of the pipe 5, and secured 50 to the pipe and to the upper portions of

the members 7 are a plurality of brackets 8 on the upper end portion of which is mounted a cap plate 9 adapted to overlie said members and pipe, while secured to the brackets intermediate said cap plate and the members 7 is an annular supplemental cap plate 10.

Mounted in the draft members 7 are a plurality of partition plates 11 suitably positioned in the members in a manner to 60 form a plurality of radially spaced upwardly tapered inner and outer passages therein, and having their upper end portions terminating in a plane above the upper edge of the pipe 5 and below the upper 65 end portions of the draft members 7.

It will be observed from the foregoing description that air currents impinging the sides of the pipe 5 will be deflected upwardly through the draft members to within the supplemental cap plate 10 and thence 70 against the cap plate 9 from beneath which they will be discharged by other currents of air, and it will be noted also that by reason of the restriction of the air 75 passages within the draft members 7, a greater velocity of the air currents is induced adjacent the upper edge of the pipe 5 and the upper edges of the members 7, thereby creating a vacuum within the pipe 5 and 80 accelerating the upward movement of the air within the pipe and chimney or ventilator flue.

To further increase the velocity of the air currents through the inner passages formed 85 between the pipe 5 and the partition plates 11, a plurality of outwardly and upwardly inclined flanges 12 are formed preferably along the leg portions of the V-shaped notches 6, thereby restricting the cross sectional draft area of the inner passages throughout a substantial portion of their length, the increased velocity of the air currents, due to the restriction of the passages, creating a greater vacuum within the interior 95 of the pipes 5 than would be the case if these flanges 12 were not provided.

To further increase the velocity of the air currents passing through the outer passages formed between the partition plates 11 and 100

the outer wall of the draft members 7, in a manner to accelerate the velocity of the air currents passing through the inner passages, a plurality of upwardly inclined flanges 13 5 are formed preferably along the upper edges of the partition plates 11, thereby further restricting the cross sectional draft area of the outer passages and increasing the velocity of the air passing therethrough.

10 It will be observed from the foregoing description that the increased velocity of the air currents passing through the outer passages due to the restricted cross sectional draft area of these passages will create a 15 vacuum adjacent the upper end of the inner passages, thereby accelerating the velocity of the air currents passing through the restricted cross sectional draft area of said inner passages, and that the increased acceleration 20 of the air currents adjacent the upper edge of the pipe 5 will tend to create a still greater vacuum within the upper portion of the pipe, thereby causing a strong upward draft through the chimney or ventilator flue to 25 which my improved top may be applied.

If it is desired, the V-shaped notches 6 may be formed in the upper edge of the chimney or ventilator flue itself and the draft members 7 and brackets 8 secured thereto, but it 30 has been found convenient to mount the draft members and co-operating elements on a short section of pipe as indicated in the drawings and attaching the said pipe to the upper end of the chimney or ventilator flue.

35 Obviously, the present invention is not limited to the precise construction and arrangement shown and described, as the same may be variously modified. Moreover, all 40 of the features of the invention need not be used conjointly, as the same may be used to advantage in variously different combinations and sub-combinations.

What I claim as my invention and desire to secure by Letters Patent is:

45 1. In a chimney top or ventilator, the combination with a pipe having a plurality of V-shaped notches formed in its upper edge, of a plurality of draft members positioned around said pipe and co-operable therewith 50 in a manner to form a plurality of upwardly tapered passages outside said pipe and adjacent said notches, a cap plate positioned above said pipe and members, and partition plates mounted wholly within said members 55 intermediate the upper and lower end portions of the members in a manner to form a plurality of radially spaced passages within said members.

60 2. In a chimney top or ventilator, the combination with a pipe having a plurality of V-shaped notches formed in its upper edge, of a plurality of draft members positioned around said pipe and co-operable therewith 65 in a manner to form a plurality of upwardly tapered passages outside said pipe and ad-

70 jacent said notches, a cap plate positioned above said pipe and members, partition plates mounted in said members in a manner to form a plurality of radially spaced passages within said members, and flanges adjacent the upper edges of said partition plates.

3. In a chimney top or ventilator, the combination with a pipe having a plurality of V-shaped notches formed in its upper edge, 75 of a plurality of draft members uniformly spaced around said pipe adjacent said notches and co-operable with said pipe in a manner to form a plurality of upwardly tapered passages outside said pipe and adjacent said notches, a cap plate positioned 80 above said pipe and members, partition plates mounted in said members in a manner to form a plurality of radially spaced passages within said members, and outwardly 85 extending flanges formed adjacent and extending along the upper edges of said partition plates.

4. In a chimney top or ventilator, the combination with a pipe having a plurality of V-shaped notches formed in its upper edge, 90 of a plurality of U-shaped draft members uniformly spaced around said pipe adjacent said notches and co-operable with said pipe in a manner to form a plurality of upwardly 95 tapered passages outside said pipe and adjacent said notches, a cap plate positioned above said pipe and members, partition plates mounted in said members in a manner to form a plurality of radially spaced inner and outer passages within said members, and outwardly 100 inclined flanges formed adjacent and extending along the upper edges of said partition plates in a manner to restrict the cross-sectional draft area of said outer passages adjacent the upper edges of said plates. 105

5. In a chimney top or ventilator, the combination with a pipe having a plurality of V-shaped notches formed in its upper edge, 110 of a plurality of U-shaped draft members uniformly spaced around said pipe adjacent said notches and co-operable with said pipe in a manner to form a plurality of upwardly tapered passages outside said pipe and adjacent said notches, a cap plate positioned 115 above said pipe and members, partition plates mounted in said members in a manner to form a plurality of radially spaced inner and outer passages within said members, and outwardly extending inclined flanges formed adjacent and extending along the sides of 120 said notches in a manner to restrict the cross-sectional draft area of said inner passages adjacent the upper edge of said pipe.

6. In a chimney top or ventilator, the combination with a pipe having a plurality of V-shaped notches formed in its upper edge, 125 of a plurality of U-shaped draft members uniformly spaced around said pipe adjacent said notches and co-operable with said pipe in a manner to form a plurality of upwardly 130

tapered passages outside said pipe and adjacent said notches, a cap plate positioned above said pipe and members, partition plates mounted in said members in a manner 5 to form a plurality of radially spaced inner and outer passages within said members, outwardly extending inclined flanges formed adjacent and extending along the upper edges of said partition plates in a manner to restrict 10 the cross-sectional draft area of said outer passages adjacent the upper edges of said plates, and outwardly inclined flanges formed adjacent and extending along the sides of said notches in a manner to restrict 15 the cross-sectional draft area of said inner passages adjacent the upper edge of said pipe.

7. In a chimney top or ventilator, the combination with a pipe having a plurality of 20 annularly spaced notches formed in its upper edge, of a plurality of U-shaped draft members uniformly spaced around said pipe and extending above the upper edge thereof, said members being adapted to co-operate with 25 the outer face of said pipe in a manner to form a plurality of air passages, partition plates mounted in the respective U-shaped members in a manner to provide a plurality of radially spaced passages within said members, the upper ends of said plates being adapted to terminate in a plane above the upper edge of said pipe and below the upper 30 ends of said members, and a cap plate positioned above said members, partition plates 35 and pipe.

8. In a chimney top or ventilator, the combination with a pipe having a plurality of annularly spaced V-shaped notches formed in its upper edge, of a plurality of U-shaped 40 upwardly tapered draft members annularly spaced around said pipe and extending above the upper edge thereof, said members being adapted to co-operate with the outer face of said pipe in a manner to form a plurality of 45 air passages adjacent said notches, partition plates mounted in the respective U-shaped members in a manner to provide a plurality of radially spaced upwardly tapered passages within said members, the upper ends 50 of said plates being adapted to terminate in a plane above the upper edge of said pipe and below the upper ends of said members, and a cap plate positioned above said members, partition plates and pipe.

55 9. In a chimney top or ventilator, the combination with a pipe having a plurality of annularly spaced V-shaped notches and upwardly inclined flanges formed adjacent its upper edge and along the sides of said 60 notches, of a plurality of U-shaped upwardly tapered draft members annularly spaced around said pipe and extending above the upper edge thereof, said members being adapted to co-operate with the outer face 65 of said pipe in a manner to form a plurality

of air passages adjacent said notches, partition plates having outwardly and upwardly inclined flanges adjacent one of their edge portions mounted in the respective U-shaped members in a manner to provide a plurality 70 of radially spaced upwardly tapered passages within the said members, the upper ends of said plates being adapted to terminate in a plane above said notches and the upper edge of said pipe and below the upper 75 ends of said members and a cap plate positioned above said members, partition plates and pipe.

10. In a chimney top or ventilator, the combination with a pipe having a plurality 80 of V-shaped notches formed in its upper edge, of a plurality of U-shaped draft members uniformly spaced around said pipe adjacent said notches and co-operable with said pipe in a manner to form a plurality of upwardly tapered passages outside said pipe and adjacent said notches, a cap plate positioned above said pipe and members, partition plates mounted in said members in a manner to form a plurality of radially 85 spaced inner and outer passages within said members, and upwardly inclined flanges adjacent and extending substantially parallel to the upper edges of said partition plates in a manner to restrict the cross-sectional draft 90 area of said outer passages adjacent the upper edges of said plates.

11. In a chimney top or ventilator, the combination with a pipe having a plurality 100 of V-shaped notches formed in its upper edge, of a plurality of U-shaped draft members uniformly spaced around said pipe adjacent said notches and co-operable with said pipe in a manner to form a plurality of upwardly tapered passages outside said pipe 105 and adjacent said notches, a cap plate positioned above said pipe and members, partition plates mounted in said members in a manner to form a plurality of radially spaced inner and outer passages within said members, and upwardly inclined flanges adjacent and extending substantially parallel to the sides of said notches in a manner to restrict the cross sectional draft area of said inner passages adjacent the upper edge of 110 said pipe.

12. In a chimney top or ventilator, the combination with a pipe having a plurality 120 of V-shaped notches formed in its upper edge, of a plurality of U-shaped draft members uniformly spaced around said pipe and adjacent said notches and co-operable with said pipe in a manner to form a plurality of upwardly tapered passages outside said pipe and adjacent said notches, a cap plate positioned above said pipe and members, partition plates mounted in said members in a manner to form a plurality of radially 125 spaced inner and outer passages within said members, upwardly extending inclined 130

flanges adjacent and extending substantially parallel to the upper edges of said partition plates in a manner to restrict the cross-sectional draft area of said outer passages adjacent the upper edges of said plates, and upwardly extending inclined flanges adjacent and extending substantially parallel to the sides of said notches in a manner to restrict the cross-sectional draft area of said inner passages adjacent the upper edge of said pipe.

13. In a chimney top or ventilator, the combination with a pipe having a plurality of annularly spaced V-shaped notches and upwardly inclined flanges formed adjacent its upper edge, of a plurality of U-shaped upwardly tapered draft members annularly spaced around said pipe and extending above the upper edge thereof, said members being adapted to co-operate with the outer face of said pipe in a manner to form a plurality of air passages adjacent said notches, inclined partition plates mounted in the respective U-shaped members in a manner to provide a plurality of radially spaced upwardly tapered passages within the said members, flanges positioned in said members adjacent the upper edge of said plates, the upper ends of said plates being adapted to terminate in a plane above said notches and the upper edge of said pipe and below the upper ends of said members, and a cap plate positioned above said members, partition plates and pipe.

14. In a chimney top or ventilator, the combination with a pipe, of a plurality of U-shaped members positioned around said pipe and co-operable therewith in a manner to form a plurality of upwardly tapered passages outside said pipe, a cap plate positioned above said pipe and members, partition plates mounted in said members in a manner to form a plurality of radially spaced passages within said members and flanges adjacent the upper edges of said partition plates.

In testimony whereof I have signed my name to this specification, on this 15th day of November, A. D. 1927.

HAROLD KNUTSON.
